UNITED STATES PATENT OFFICE.

EZECHIEL WEINTRAUB, OF LYNN, MASSACHUSETTS, ASSIGNOR TO GENERAL ELECTRIC COMPANY, A CORPORATION OF NEW YORK.

PRODUCTION OF HIGH-FREQUENCY CURRENTS.

1,131,190.

Specification of Letters Patent.

Patented Mar. 9, 1915.

Application filed June 18, 1910. Serial No. 567,568.

To all whom it may concern:

Be it known that I, EZECHIEL WEINTRAUB, a citizen of the United States, residing at Lynn, county of Essex, State of Massachusetts, have invented certain new and useful Improvements in the Production of High-Frequency Currents, of which the following is a specification.

My invention relates in general to the production of periodic currents suitable, for example, for space telegraphy and telephony and allied arts, and it involves the use of a vapor arc, having inherent unidirectional conductivity, such as the mercury arc, in a circuit containing electrical capacity. While the pulsations produced in accordance with my invention are not limited in their application to any particular system they are of such a nature as to be especially suitable for producing oscillations of one period in a work circuit in loose inductive relation with the pulsating circuit.

Some of the objects of my invention are as follows: To produce high frequency currents in a circuit having electrical capacity and connected to a vapor electric device, which circuit may be inductively related to a work circuit; to produce high frequency pulsations passing through a conductor in one direction only; to provide a method of changing and distributing electrical energy whereby oscillatory energy of high and low voltage and high or low frequency may be developed from a low voltage source which may be either direct or alternating. As will be pointed out hereafter the frequency of the periodic current may be readily controlled in accordance with my invention, and if desired, currents of very high frequency can be produced.

It has been suggested heretofore to employ the mercury arc with a condenser connected in shunt thereto, for producing high frequency currents but the arrangements have always been such as to produce an oscillatory discharge of the condenser through the arc. In accordance with my invention the arc acts as an interrupter having remarkable characteristics both with respect to the regularity and number of interruptions and the suddenness of the interruptions, which cause the condenser discharges to take place as a single impulse as will be hereinafter explained in detail.

Some of the features of my invention are

the use of a side branch, or auxiliary arc, in conjunction with the main arc in the vapor electric device; the efficient control of the temperature of the vapor electric device; the special construction and dimensions of the container in which the vapor arc is produced; the use of de-ionizing agencies operating in conjunction with the arc in order to increase the rapidity and abruptness of the interruption of the current in the arc; the control of the position and movement of the cathode spot of the vapor arc operating on periodically varying currents. These various features of my invention will be more specifically described and their operation explained in the following description taken in connection with the drawings accompanying the same and forming part of this specification.

In these drawings Figure 1 is a diagrammatic representation of a vapor electric device, connected to a source of energy, and cooled by a moving fluid, and arranged for connection to certain other elements in such a way that high frequency pulsations may be established; Fig. 2 is a fragmental view of a vapor device provided with means for controlling the movement of the cathode spot; Fig. 3 shows a system wherein a vapor tube, connected across a capacity circuit, has a part of small diameter; Fig. 4 shows a system in which a vapor device, connected across a condenser circuit, comprises a tube adapted to run at high current densities; Fig. 5 shows a system wherein a vapor device, connected across a source of energy, is provided with a plurality of tubes, or passages, through which the vapor arc may go; Fig. 6 shows a system wherein a vapor device, coöperating with a condenser circuit, has an annular path through which the vapor arc is set up, and is otherwise specially constructed for the control of the periodic currents of the system, and furthermore, is provided at the cathode with special means for governing movement of the cathode spot; Fig. 7 is a perspective view of the plate used at the cathode in Fig. 6; Fig. 8 illustrates a system wherein the vapor device has large anode and cathode chambers, but a small cross section throughout part of its length, and is equipped with a specially cooled anode. This vapor tube is shown as located in the path of a very cold fluid. Fig. 9 is a detail of the anode shown in Fig. 110

8; Fig. 10 represents a system wherein the vapor tube which shunts the condenser circuit is specially constructed and equipped to control the de-ionization of the arc path 5 through the tube and includes a conductive body located in or near the path of the arc; Fig. 11 is an enlarged detail of the conductive body shown in Fig. 10. Fig. 12 shows a modified form of de-ionizing body.

10 In the system represented diagrammatically in Fig. 1, the vapor device is connected across a source of electrical energy represented by line conductors 1 and 2. A resistance 3 and a reactance coil 4 are interposed between the vapor device and the source of energy, and an ammeter A may be used to measure the current flowing in the circuit. The vapor device here shown comprises an evacuated glass tube 5 having at 15 its top a hollow anode 6, which consists preferably of graphite. The cathode 7 consists of mercury, or other suitable vaporizable material, and is carried at the lower end of the tube. The main body of the tube shown has a diameter of, say, three-fourths of an inch, and a length of, say, eight to ten inches, and has its top enlarged somewhat to form a condensing chamber 8 surrounding anode 6. The vapor device is 20 provided with a side branch circuit comprising a small auxiliary anode 9, arranged in proximity to the cathode. Current is supplied to anode 9 by a battery 10, connected through a resistance 11 to the cathode lead 25 of the vapor device. Battery 10 is effective to maintain a continuous, short, side branch arc between the auxiliary anode 9 and the vaporizable cathode 7. In addition to the elements just described, the system comprises 30 a circuit having switches 12 and 13, whereby it may be connected to the respective terminals of the vapor device. This circuit has electrical capacity, and inductance and may contain an ammeter I. The 35 capacity is here represented diagrammatically by a condenser 14, which may be of ordinary type and adjustable. The inductance may in some cases be as small even as that afforded by the conductors leading 40 to and from the condenser; in other cases the winding of a transformer or induction coil may be used. For purposes of diagrammatic representation, the circuit is shown as having a reactance coil 15 (which may be 45 omitted) and a winding 16, the latter serving to transmit energy to a work circuit, as hereinafter set forth. It will be understood that in this figure, as in other figures of the specification, these coils and the condenser are used as diagrammatic symbols of the reactive condition of the circuit. In the diagram, a winding 17 is shown in inductive relation to winding 16. These windings 50 may have an iron core, or no core, as best suits the work at hand. In case the arrange-

ment is to be used for space telegraphy the winding 17 is connected respectively to the antenna 18 and ground wire 19. The inductive connection afforded by primary coil 15 and secondary coil 17 is preferably what is known in the art as a "loose coupling" so that when electrical pulsations are impressed upon the primary the secondary will oscillate, when properly tuned, in one period only, a period determined by the capacity and inductance of the antenna circuit. The sharpness of the discharges occurring in the primary circuit is especially well adapted for exciting a "loosely coupled" circuit. The winding 17, and the aerial and ground wires are intended to indicate diagrammatically a work circuit in which oscillatory effects may be induced and utilized. Winding 16 is effective to develop a high frequency electromotive force in winding 17, and winding 17 may be used as a source of energy for many of the various kinds of work circuits that have been used in connection with spark gap phenomena and in connection with telegraphic and telephonic communication through space. These work circuits are so well known and so varied in character that my invention can best be disclosed by considering the work circuit of Fig. 1 as a diagrammatic representation of other work circuits, whether syntonic or otherwise, damped or undamped, arranged for high frequency or low frequency, high voltage or low voltage, and whether continuous in action or intermittent. The application of my invention is, of course, not limited to space signaling. It may be applied to any of the various uses to which a high frequency pulsating current is applied. The tube 5 is artificially cooled as indicated diagrammatically by the motor driven fan 20 and the arrows. The importance of cooling will be later discussed.

With the elements grouped as above described, and with switches 12 and 13 open, and the side branch arc playing to cathode 7, the application of a relatively low voltage across conductors 1 and 2 will cause current to pass from the source through resistance 3 and 4, and from anode 6 to cathode 7, and back to the source. If the source is a direct current source, this flow of current will be continuous. If it is alternating, the flow will be discontinuous, because of the rectifying action of the vapor device.

When the switches 12, 13 are closed, two cases can be distinguished. If the direct current flowing in the main circuit is above a certain value, which depends on the capacity of the condenser 14, and on the size of the inductances 15 and 16 while the side branch is running, it will be found that the mere closing of switches 12 and 13 will not disturb the main arc. Apparently under these conditions, the arc continues to run in

normal manner, and the ammeter I shows no appreciable current in the condenser circuit. If, however, the vapor device is running on a direct current smaller than this 5 the closing of the switches 12 and 13 may effect a marked change in the nature of the current flowing in the vapor device, and may cause the arc current to become a pulsating one. A periodic current will then be indicated by ammeter I, and can be used to convey energy to the winding 17 of the work 10 circuit.

The phenomena involved may be explained as follows: When the switches 12 15 and 13 are closed, current is diverted from the vapor device to charge condenser 14 which at that instant is incapable of exerting a strong counter electro-motive force. As the result, the voltage across the vapor 20 device drops to such a low value that the arc from the main anode can be maintained no longer. With the arc extinguished, the condenser takes on its full charge, the charging current progressively decreasing as the 25 charge builds up. With this progressive decrease in current, the voltage drop across resistance 3 and reactance 4 decreases, and the voltage impressed on the tube rises to a value at which the main arc can start again. 30 Owing to the inherent characteristics of the vapor device, the voltage at which the arc, re-starts, is materially higher than that at which the arc goes out. But, on the reestablishment of current flow through the tube, 35 the rapidly increasing ionization caused by the current increases the conductivity along the arc path, and gives the condenser a discharge path of such a character that the condenser discharges with great rapidity. 40 The cycle of alternate charge and discharge repeats itself with great rapidity.

Expressing the phenomena in different language, it may be said that the circuit which contains capacity and inductance and 45 is connected in shunt to the mercury arc tube, diverts electrical energy from the arc for a period long enough to allow the arc to cool, and then discharges backward into the arc path, which, however, does not re-start 50 the arc until the potential goes higher than that at which the arc started to cool.

Whatever the explanation, the ultimate result is that high frequency and high potential effects are set up in the circuit connected 55 across the mercury arc terminals and can be used as a source of power for induction coils, or in wireless telephony and telegraphy, or wherever a long or powerful spark, or a periodic, or pulsating discharge 60 at high frequency is desired.

The alternate charge and discharge of the capacity circuit as described, takes place at a rapid rate. The rate is dependent in a measure on the amount of capacity in the

circuit and on the amount of inductance effective to impede the charging and discharging current. The current alternately charging and discharging the condenser is referred to hereinafter as a pulsating current to distinguish it from the oscillations in the antenna. I have found that the changing conductivity of the arc and the unidirectional character of the arc path introduce factors influential in controlling the action of the system and the frequency of the pulsations.

The unidirectional character of the condenser discharge is mainly due to the use of the side branch arc which is constantly maintained at the cathode. As the result of the 80 constant operation of the side branch, the current flow through the tube is in the direction from the anode 6 to cathode 7. Not only does the tube act as a valve, or rectifier for current supplied directly from the source, but it also acts as a rectifier with respect to the condenser discharge; in other words, the condenser must discharge itself through the tube each time in a single impulse. Except for this rectifying action of the vapor device, the discharge of the condenser would be oscillatory in character, and would persist after the first rush of energy had occurred. In the arrangement with the side branch, the mercury arc may be regarded as an interrupter, and more particularly as an interrupter of remarkable characteristics, both with respect to the number of interruptions possible per second, and with respect to the rapidity at which 90 interruptions occur. The side branch arc, by keeping the cathode excited, also makes it possible to operate the arrangement at lower impressed voltage and makes the restarting 95 voltage a regular and definite quantity.

I have found that the magnitude of the impressed voltage and speed at which the tube is ionized and de-ionized are of importance in determining the frequency of the pulsations and the magnitude of the power that can be transmitted. A concrete illustration referring to the tube in Fig. 1 may be given here. Assume that the source of energy is direct current at 500 volts, and that resistance 3 and inductance 4 are so adjusted that with a condenser circuit containing 36 microfarads capacity, and very little inductance, a current of 0.3 amperes will flow at A and a current of 0.7 amperes at I. Under these conditions, the pulsations in the capacity circuit will come with a frequency of about 3,000 per second. The main arc flowing between anode 6 and cathode 7 will be unidirectional in character. On the antenna circuit sustained oscillations 100 will be produced.

When the main arc is running and developing a periodic current in the capacity

circuit, a decrease in the value of resistance 3, to increase the current at A, will produce an almost proportionate increase in the pulsating current at I, and thereby will effect 5 an increase in the energy converted into pulsating current. Above a certain current, depending on the value of the capacity, the inductance, the diameter of the tube and other factors to be identified later, the tube 10 runs without pulsations.

I have discovered that the temperature of the vapor device has a controlling influence 15 on its operation as an interrupter in the manner indicated above and also on the frequency and magnitude of the pulsations obtainable in the capacity circuit which is in shunt with the device. I have found that the speed of de-ionization is greatly influenced by the temperature and I have found 20 that by using a blast of air or stream of oil the temperature can be controlled and thereby the speed of de-ionization can be controlled. Water cannot be used as a cooling agent, possibly because of its conductivity. 25 As the mercury arc is inclosed and in a vacuum, the cooling can be very efficient much more so than would be possible with, for example, a carbon arc. The cooling is more effective than is possible with other 30 forms of arc also, because of the small mass of matter to be cooled.

While I have explained the operation of the system without reference to the cooling, for the sake of simplicity, I find that the 35 pulsations ordinarily will not be produced without artificial cooling or can be produced only for a few seconds at a time, or at most minutes, depending on the external conditions. Especially for higher values of 40 the current at A than given above, the de-ionization speed of the tube will be so altered that the current at I will drop off to substantially zero.

With a tube as shown in Fig. 1 consisting 45 of glass with a diameter of $\frac{1}{4}$ of an inch and a length of 8 to 10 inches, enlarged at the top into a condensing chamber as indicated, a blast of air delivered by a small fan as indicated at 20 is sufficient as a cooling 50 means to cause the apparatus to work with regularity even at values of current at A materially above that already indicated. For many purposes, however, particularly in aerial signaling, a frequency much higher 55 than 3,000 is desirable. For some aerial work, the oscillations must occur as rapidly as 100,000 times a second, and also must deliver considerable power at that frequency. To obtain higher frequency oscillations and 60 more power, my investigations have been pushed far beyond the simple relation illustrated in Fig. 1.

Inasmuch as the natural vibratory period 65 of the capacity circuit is inherently dependent on the amount of capacity it contains,

and on the amount of inductance in circuit with that capacity, it might be assumed that in the system shown in Fig. 1, the frequency of the pulsations could be controlled solely by changes in the reactive character of the 70 condensed circuit. But such is not the case. If the condenser 14 were made very small, and therefore capable of charging and discharging quickly, and capable of giving to the condenser circuit the inherent qualities 75 of short periodicity, the condenser circuit may be so rapid in operation as to fail in its coöperative relation to the vapor tube. For instance, the condenser may be charged so quickly, and may divert from the tube such 80 a small amount of energy that the voltage across the vapor arc will not drop below the critical voltage. In such a case, the arc will continue to run, and no pulsating current will be set up.

Looking at the situation from a different standpoint, it may be said that the vapor device of Fig. 1 is so sluggish in its action that it is unsuited for use with a condenser circuit having an inherent period of pulsation, shorter than a certain fixed value.

I have determined experimentally that whatever the size of the condenser used in the capacity circuit, it must be large enough to effectively rob the tube of its arc current, 95 and must take on its charge so slowly that the increase in potential across the capacity circuit will not go up too fast for the sluggish vapor electric device. In other words, the potential across the vapor tube must not 100 rise so rapidly as to allow the tube insufficient time for its de-ionization and recovery to a condition of low conductivity. As previously indicated, the complete recovery of the tube will be accompanied by a starting 105 voltage much higher than that at which the arc went out; and if the voltage applied to the vapor tube by the charging condenser goes up too rapidly, the arc will be re-established without having really gone out, 110 and the arc voltage will not attain that high value desirable in transmitting a considerable quantity of energy efficiently.

In order to produce very high frequencies, I have had recourse to various changes 115 in the system, as hereinafter recited at length. Also certain features have been modified to increase the amount of energy that could be made available for useful work in a work circuit.

The above discussion has been directed more particularly to a system supplied with current from a direct current source, but I have ascertained that in the system of Fig. 1, as in all the others illustrated in this application, an alternating current can be used with much the same general effects and results as a direct current.

A transformer having any desired voltage can be connected to the line conductors 120

and the maximum voltage available for starting the arc as the condenser recharges, can be made correspondingly great. Furthermore with this arrangement the effect of any disturbance of the conditions in the arc is limited to a half period of the applied voltage, since the arc starts anew at each period. Reactance instead of resistance may be relied on to limit the main line current. 5 A higher efficiency than that found with the direct current supply, and the assurance of uniform operation under variable conditions, inherent in the use of an alternating current source are obtained. But an alternating current supply divides the resultant pulsations into groups, because of the suppression, or rectification of alternate half-waves, of current. However, as the fundamental features of my invention can be made clear without particular reference to the nature of the current source, whether alternating or direct, the description of other figures will, for the sake of brevity, contain little or no reference to an alternating current source, though, as 10 above stated, the advantages of such a source may be material.

The theory and mode of operation as above applied to Fig. 1 is applicable also to the systems illustrated in the other figures 15 of the drawings.

I have discovered that a rod projecting from the surface of the cathode has a marked effect in increasing the quantity of energy that can be transmitted and the 20 regularity of pulsations obtainable from a system in which a vapor electric device is connected across a source of power and in shunt with a capacity circuit.

Fig. 2 is a fragmental view of a vapor device, having a tubular envelop 21 and cathode chamber 22, of the same size and shape as those shown in Fig. 1. A rod or block 23 projects above the surface of the mercury, and serves to limit the movement 25 of the arc seat, or cathode spot. This block may be of copper and may float on the surface of the mercury, or may be anchored to the leader - in conductor 24, as indicated. The rod is preferably grooved or roughened 30 at its upper end, and is wet by the mercury and carries the cathode spot of the arc. Not only does it serve to limit movement of the cathode seat or spot, but it acts to limit the quantity of mercury vaporized by the arc. 35 It makes the tube run cooler on a given arc current, and it influences in some way the static conditions in the tube, freeing the tube from many of the troublesome effects so commonly experienced with a circuit which 40 contains reactance. This cathode rod also may have other functions contributing to an increase in the effectiveness of the vapor device as a component part of the system illustrated. The increased regularity of oscillation due to the fixing of the cathode spot

allows the use of higher main current and thus, the derivation of higher energy in the oscillation current. Furthermore, I have found that the use of the rod decreases the sluggishness of the vapor device, thereby 45 making the tube effective for use with smaller condensers, resulting in pulsations of higher frequency. I have discovered that the cross section and length of the envelop of a vapor electric device has a controlling 50 effect on the frequency of the interruptions. The narrower the tube, the higher the number of interruptions possible, and the higher the efficiency. A decrease in cross-section of the tube increases the starting voltage. An 55 increase in the voltage at which the pulsations are obtainable facilitates the delivery of more power in the work circuit.

Fig. 3 is a diagrammatic representation of a vapor device, cooled by a circulating 60 fluid and having an envelop with a tubular portion 25, which has a bore of three-eighths to one-eighth of an inch, or even smaller, and a length of eight to ten inches. This tubular portion carries at its top a considerable 65 enlargement 26 which serves as a condensing chamber, and incloses a hollow graphite anode 27. The tube has at its lower end an enlargement 28, serving as a cathode chamber for a cathode 29, and this has a 70 cathode rod 30 of the type previously described, and also has a side branch arc which is maintained at the cathode by an auxiliary anode 31 receiving current from a battery 32 connected to the cathode lead-wire 75 through a resistance 33. When the line conductors 34 and 35 are connected to a source of direct current, or of alternating current, the current will flow through the non-inductive resistance 36 and the inductive resist- 80 85 90 95 100 105 110 115 120 125 130

ance 37 and will pass from anode 27 to cathode 29, and may be read at ammeter A, which is connected in the line conductor 35. If the capacity circuit connected in shunt with the vapor device of $\frac{1}{16}$ " bore by 6" length has in circuit a condenser 38 and an inductance 39, and a winding 40, and has a total capacity of 0.01 microfarad and a total inductance of 0.01 microhenry, the passage of 0.5 amperes at A will be accompanied by the passage of 3.5 amperes at I, and the pulsating periodic current in the capacity current will have a frequency of 80,000 pulsations per second and can be utilized to deliver energy to a work circuit. This work circuit may include a winding 41 in inductive relation to winding 40. It is shown in this case as being connected to an adjustable spark gap having terminals 42 and 43. It is connected to an aerial 44 and a ground conductor 45. Cooling by means of air is indicated diagrammatically by arrows. The spark gap here indicated may, of course, be used if desired with any of the modifications described. When the system is in operation

- it may be opened beyond striking distance for ordinary voltages and act as a sort of safety valve for excess voltages. I have discovered that the envelop of the vapor electric device can with advantage have a very long, constricted, cylindrical portion through which the main arc is caused to pass. Also, it may have with advantage, a large anode chamber and a large cathode chamber.
- 5 10 Also I have found that the cooling of the envelop with a fluid, may to advantage be forced, as by using a very powerful fan. The constricted nature of the arc path contributes toward a high operating efficiency
- 15 and a high speed of de-ionization, and the cooled envelop keeps down the vapor in the tube and helps to eliminate whatever of sluggishness, or persistence might otherwise be present in the arc.
- 20 The discussion of operation applied to Fig. 1 may here be applied, also, but this system is more particularly directed to high frequency and to high power and to high efficiency and the size and shape of the tube
- 25 and the functions of its several parts as cooling or de-ionizing agents for the arc, contribute to those ends. The specific values of current and frequency here given are of interest as showing some of the possibilities of
- 30 35 a vapor-tube of very special shape, effectively cooled.

When using a tube about $\frac{1}{16}$ " in diameter, in a system as shown in Fig. 3, with a powerful fan, a line potential of 1200 volts, a current of 1.8 amperes direct current indicated at ammeter A, and with a capacity circuit including 0.25 mf. capacity and 0.5 mh. inductance, a current of 8 amperes may be found at ammeter I. The pulsations in

40 45 the capacity circuit may have a frequency as high as 10,000. This high frequency current passing through the primary of the loosely coupled transformer produces sustained oscillations in the secondary, and the energy becomes available in that circuit for use in electric signaling.

The principles of a constricted arc path with suitable de-ionizing agencies and a cathode spot having limited movement can be used as the means for attaining frequencies as high as 100,000 per second and higher, and of such power as to be very well suited for use in emitting electro-magnetic waves for signaling. This can be done at an efficiency and a maximum output far superior to the systems heretofore proposed for this purpose.

With a tube having a bore of about $\frac{3}{16}$ ", and with a capacity of about 0.025 microfarad, and with little inductance in the condenser circuit, pulsations giving a meter reading of 5 amperes, at a frequency of 40,000 per second are obtainable when the line ammeter reads $\frac{3}{4}$ amperes. With an inductance of 0.25 microhenry added to the

condenser circuit, pulsations giving a meter reading of 3.5 amperes at a frequency of about 60,000 per second are obtainable. Tubes having a diameter as low as $\frac{1}{16}$ " give still higher frequencies. With a capacity of 0.02

70 mf., inductance of 0.01 mh. and a line current of 1.1 amperes, a current of 5 amperes is indicated at I with a frequency of 100,000 per second.

Fig. 4 illustrates a system in which the vapor device consists in part, at least, of quartz to enable it to be run with higher current densities. In the construction shown, the intermediate constricted portion 46 of the vapor tube is of quartz and has a length of about $4\frac{1}{4}$ inches and a bore of about $\frac{1}{16}$ inch. It is provided at its top end with an enlargement 47 fitting with a ground joint to a glass bulb 48 which constitutes a condensing chamber about the hollow graphite anode 49. This condensing chamber may have a diameter of 3 inches. At the lower end of the device, the quartz tube is enlarged at 50, and fits about a glass receptacle 51 which is about $1\frac{1}{4}$ inches in diameter, and contains the cathode 52 of mercury or other vaporizable material. A copper rod 53 projects above the surface of the cathode. A side branch arc can be maintained from the auxiliary anode 54, supplied with currents from a battery 55 connected to the cathode lead through a resistance 56. Shunted across the vapor tube is a capacity circuit illustrated as containing a condenser 57, an inductance 58, and a winding 59, acting as the primary of a "loosely coupled" transformer having a secondary 60.

The general mode of operation is analogous to that of the apparatus shown in Fig. 1. When current at 1200 volts D. C. is supplied through the line conductors 61 and 62 by way of the non-inductive resistance 63, and inductive resistance 64, pulsations of high frequency are set up in the capacity circuit. As in the system previously described, the periodically changing current through winding 59 produces oscillations in its co-operative winding 60 and energy becomes available in the form of high frequency energy suitable for use in the aerial 65, and ground conductor 66. The quartz tube is cooled, as indicated by arrows by a strong, cold air blast. With a tube of the shape and dimensions above set forth, and a line potential of 1200 volts D. C. and with a condenser circuit having 0.01 mf. capacity and 0.01 mh. inductance, impulses of a frequency of 80,000 may be impressed on the work circuit with a current of $3\frac{1}{2}$ amperes

105 110 115 120 125 130 as measured at ammeter I and a current of .5 amperes as measured at ammeter A. An input of 600 watts from the direct current source gives an output of 456 watts periodic current, or an efficiency of about 75%. In

this apparatus, a rather large side branch current should be used to prevent the cathode spot from being driven off its rod by the heavy and violent pulsations. The 5 success in the transformation of so much energy at such a high frequency is due in a measure to the rectifying action of the tube and to the rapidity of the de-ionization in the narrow tube with its cathode rod and to 10 its rapidly moving and cold cooling fluid.

In Fig. 5 the vapor electric device is subdivided into two constricted tubes 67 and 68, each having a diameter of about $\frac{1}{16}$ " and a length of about 6" and both communicating 15 with the enlarged upper chamber 69 in which the hollow graphite anode 70 is located. At their lower ends, these tubes open into a horizontal chamber 71, and at one end of this is a mercury cathode 72. 20 This cathode has a copper rod 73 projecting from its surface as in the system of Fig. 4 and is so located that the cathode vapor passes directly upward into an enlargement 74. A side branch arc is continuously 25 maintained between the auxiliary anode 75 and the cathode 72 by means of a storage battery 76 acting through a resistance 77. With a pressure of 1200 volts direct current impressed on the line conductors 78 and 79, 30 and a main line current of 0.9 amperes flowing through the usual non-inductive resistance 80 and inductive resistance 81, a current of 5 amperes will be indicated at ammeter I, as the current flowing through the 35 capacity circuit connected in shunt with the tube. This circuit is diagrammatically represented as including a reactance coil 82, a condenser 83, and a winding 84 in inductive relation to a second winding 85 which forms 40 part of a work circuit. The terminals of winding 85 are shown connected to an aerial 86 and a ground plate 87; as in other figures. Tubes of this special shape have the advantage of rapid cooling, rapid de-ionization 45 and relatively high capacity for current, without undue heating. The arc appears to the eye as running in both branches of the tube, though it is probable that the arc changes from one to the other alternately at 50 a rapid rate. More than two branches can be used thus and by using enough small tubes in parallel and allowing the arc to shift from one to another, the glass is protected from overheating even at heavy currents, and effective de-ionization is insured. 55 In other particulars, the explanation applied to Fig. 1 can be applied here also. Rugged tube structure and rapid de-ionization of the vapor can be achieved by making the arc 60 run in an annular space between two cylinders. If the annular space has a width of say $\frac{1}{16}$ " to $\frac{1}{8}$ " the de-ionization can be accelerated by cooling the arc both from the inside and the outside. The large cross section 65 allows large currents to pass and thus

renders large quantities of energy available in the work circuit.

In the system shown in Fig. 6, the vapor electric device comprises an envelop having a tubular portion 88 communicating at its upper end with the large condensing chamber 89, and communicating at its lower end with the cathode chamber 90. The graphite anode 91, which is mounted in the condensing chamber 89, is of annular shape. Projecting downward from the extreme upper end of the tube is an inner tube 93, closed at its lower end and open to the atmosphere at its upper end. A tube 94 projects nearly to the bottom of tube 93 and serves to introduce a cooling fluid. The concentric relation of tube 93 and the outer wall of the envelop establishes an annular space having a length of about 5 inches a perimeter diameter of $\frac{1}{4}$ inch and a distance between the inner and outer walls of about $\frac{1}{32}$ inch. Through this annular space, the main arc passes from anode 91 to the mercury cathode 95. The auxiliary arc, or side branch, is maintained by means of an auxiliary anode 96 supplied by current from a battery 97 connected in series with the usual resistance. Such a tube combines the advantages, among others, of large cross section of arc, efficient cooling and mechanical strength. 95 In the construction shown, the mercury cathode 95 is surmounted by a copper plate or disk 98, perforated by a number of small holes 99. As indicated in Fig. 7 the leading-in wire 100 may pass loosely through a hole 100 in the plate so as to allow the same to float freely on the mercury. The mercury of the cathode wets this copper plate, and the small amount of mercury held in the tubes or perforations 99 form centers from any of 105 which the arc may emanate. If the cathode spot is driven from one center by the violence of the pulsations, it can find another center without moving far, and even when the cathode spot is driven from point to point, the irregularities introduced do not cause the arc to go out. By spacing the holes close together, the irregularities can be made small and the tube can be made to 110 operate on higher currents than when a single cathode rod is used, though, in general, the cathode plate has the advantages, characteristics and functions of the cathode rod as recited in connection with Fig. 2.

The operation of this tube is analogous to that of the systems shown in other figures. Current having a frequency of 80,000 per second at 5 to 6 amperes and more can be produced in the capacity circuit, when a pressure of 1200 volts D. C. is applied by the line conductors 101 and 102 by way of the non-inductive resistance 103 and the inductive resistance 104. The capacity circuit is here illustrated, as in the other figures, by 115 an adjustable condenser 105, an inductance 120

106 and a winding 107, the latter having a loose inductive coupling with a winding 108 connected to an oscillation work circuit which is indicated diagrammatically by the 5 aerial 109 and the ground conductor 110. A vigorous circulation of air is maintained about the tube, not only outside, as in the systems previously described, but also inside by way of the depending inner tube 93. In 10 running these and other tubes at high periodicity, I have noticed that if the operator brings his hand near the tube, the frequency of the pulsations may change, and in some cases, the arc may even be extinguished. A 15 large block of paper brought near the arc causing little or no effect, but a sheet of copper held in the hand has very great effect. If the copper be insulated from the hand and again approached, it has a slight effect. 20 A graphite anode used in a vapor device carrying current pulsations which run to a very high maximum value has the property of depositing carbon particles on the upper part of the constricted portion of the 25 tube, and that constricted portion, right where it joins the upper bulb, may, for this reason, get very hot. A cooled copper anode does not show this effect. Also, a copper anode, if properly cooled as hereinafter 30 described, offers material advantages as a de-ionizing agent in the upper part of the tube. Although its sphere of action as a de-ionizing means may not be great, its effect on the arc path as a whole is very noticeable, 35 and of importance.

I have discovered that by increasing the volume of the cooling blast even greater than that contemplated in the systems described above, and by using a big blower instead of a fan motor, the main line current at which the tube is capable of running can be very much increased. Also the cooling blast, which may be air, can with advantage be first passed through a refrigerating 40 mixture. These principles and other details are illustrated in Fig. 8.

Fig. 8 shows a system arranged more particularly for the production of pulsations of moderate frequency, such as might be useful in the operation of apparatus now commonly actuated by induction coils. In the system shown, the vapor electric device has an envelop with a tubular portion 111 which is 8 to 10 inches long and $\frac{3}{8}$ to $\frac{1}{4}$ of an inch 45 in diameter and terminates at its upper end in a spherical enlargement or chamber 112 having a diameter of about 3". At the lower end of the envelop is a cathode chamber 113, in which is a mercury cathode 114 50 surmounted by a perforate copper block 115 of the kind shown in Fig. 7. An auxiliary anode 116 is connected with a battery 117, and resistance 118 to furnish a side branch arc to the cathode. The main anode of the 55 vapor device is preferably of the type shown

in Fig. 9 and comprises a copper or brass cup 119, butt-welded to a platinum tube 120, which is fused into the top of the glass envelop. Projecting downward into this copper anode 119 is a tube 121, whereby cooling 70 air may be projected into the copper cup. Water is not suitable as the cooling medium for an anode of this kind because of the danger of condensing mercury vapor on the anode, thereby forming what is virtually a 75 mercury electrode capable of operating as a cathode for reverse pulsations of current. Mercury anodes are not suitable for tubes used in this way. By using air as a cooling fluid, a large quantity of heat can be transported 80 from the electrode without the danger of lowering the electrode below its most efficient temperature, and without danger that the condenser will discharge backward 85 through the vapor device. The blower 122, 90 whereby the cooling air is circulated should be of powerful construction and may take its supply of cold air from a refrigerating machine or the like, as indicated by the tubes 123, through which a cooling fluid is circulated. The main arc is run from a source of direct current or alternating current represented by the line conductor 124 and 125, the current passes to the anode 119 through a non-inductive resistance 126 and an inductive 95 resistance 127. The capacity circuit, as in the other figures, is represented diagrammatically by a condenser 128, connected through an inductance 129 and a winding 130 to the terminals of the vapor device. 100 Winding 130 may be one winding of an inductive coil of which the other winding 131 (which may have fewer or more turns) is connected to adjustable sparking terminals 132. Operating the system at 500 volts on 105 the arc and an in-put of 0.3 amperes, the arrangement can be run continuously without difficulty, a result practically impossible with the hammer and break interrupter. The small amount of energy needed 110 for maintaining the device insures a high operating efficiency as compared with the ordinary hammer break interrupter. This arrangement may, of course, be used in connection with a sending circuit in the same 115 manner as the arrangement illustrated by Fig. 1.

I have discovered that de-ionization may be influenced and in large measure controlled by the presence of a conductive body in the path of an arc when the arc is used in shunt with a capacity circuit. Furthermore, I have discovered that the rapidity with which the de-ionization occurs is dependent on the conductivity of the material used for the conductive body. This gives a method and a means for controlling the frequency of the pulsations produced by the system.

Long metal tubes in contact with the arc 118

and close to the walls of the vessel, prevent the formation of pulsations altogether, unless the voltage is very high, but if the tubes are sufficiently short, pulsations take place, 5 and the de-ionized effect of the metal shows itself in the possibility of producing pulsations of exceedingly high frequency even though the tube be of relatively large cross section. Graphite and silicon tubes have 10 the same action, also a thin coating of platinum. The effect can not be due to the change in the static field caused by the presence of the cylinder, since a metallic tube wrapped around the outside of the glass 15 does not have the same effect.

Metals placed inside the tube in the path 20 of the arc, either in the form of diaphragms having a hole or in the form of little cylinders surrounding the arc, exert the de-ionization effect above referred to and are effective to regulate the frequency of pulsations and the voltage at which the arc re-starts after each going out. The description 25 of a tube embodying conductors of this nature will serve as an illustrative embodiment of this feature of my invention, and will serve to disclose the basic principles.

The system shown in Fig. 10 embodies 30 many of the details illustrated in other figures, but contains as an additional element a small conductive body located adjacent to the path of the pulsating arc. The presence of this conductor allows much more energy to be derived in the form of oscillations at the same main current, and also permits an increase in the maximum main 35 line current at which pulsations take place with a given capacity. The general effect of the conductor in the arc path seems to be 40 to raise the voltage necessary for the re-starting of the arc. Although the size, shape and location and also the conductivity of the conductive body may be varied through wide limits, the following description 45 of tubes embodying conductors which in the one case is a cylinder, and in the other case a perforated plate, will serve to give a general idea of the de-ionization power of such a conductive body.

50 In the system shown in Fig. 10, the vapor device has a constricted tubular portion 134, which may have a length of six to eight inches and a bore of, say, $\frac{1}{2}$ to $\frac{1}{8}$ inches. At the top, this constricted portion opens into 55 a very large condensing chamber 135 operative as a de-ionizing agency. At the lower end the constricted tube opens into a large cathode chamber 136. The anode 137 is of the water-cooled type shown in Fig. 9, and 60 discussed at some length in connection with Fig. 8. The mercury cathode 138 is sur-mounted by a perforate copper block 139 of the kind shown in Fig. 7, and it performs the functions recited in connection with the 65 description of those figures. The side branch

arc can be continuously maintained from the auxiliary anode 140 by a storage battery 141 in circuit with the resistance 142. The source of energy may be either direct current or alternating current, and the current is supplied through line conductors 143 and 144 by way of a non-inductive resistance 145, and an inductive resistance 146. In this figure, as in the preceding figures, the capacity circuit is indicated diagrammatically by 70 an adjustable condenser 147 as inductance 148, and a winding 149. The latter is in inductive relation to the work circuit, shown as comprising a winding 150 and an aerial 151 and ground wire 152.

80 Located somewhere along the arc path of the vapor device is a conductive body 153 adapted to serve as a de-ionizing agent. This body is shown in the enlarged detail view in Fig. 11. Under some circumstances 85 the de-ionizing action of this conductor may be too great. If the tube 134 be very long, the de-ionizing action may be so great that even on a line voltage of 1200, the main arc will go out and stay out. Under such a condition, the condenser, though rising in voltage 90 as time passes, never quite reaches a potential high enough to re-start the arc. The size of the conductive body must therefore be adjusted in accordance with the bore 95 of the tube and in accordance with the electrical characteristics of the circuit and the result desired. If the conductive body be in the form of a tube of copper, one-fourth of an inch long and three-eighths of an inch 100 outside diameter, with a one-eighth inch hole bored through it lengthwise, the tube will be suitable for use on moderate potentials in conjunction with capacity circuits of the general character heretofore described in 105 connection with other figures of this application. I have discovered that the electrical conductivity of the body governs its de-ionizing action. Tubes of silicon have less effect than similar tubes of copper, and tubes 110 of glass have little or no effect. Shortening the length of the cylinder has the effect of decreasing the de-ionizing action. The position of the metal in the arc is of influence. To attain de-ionization with metal, but at 115 re-starting voltage somewhat lower, a single plate of metal can be placed transversely in the tube about half way between the cathode and anode, as indicated at 154 in Fig. 12. With this arrangement, I have found that 120 the plate aids greatly in producing de-ionization, and that the tube is thereby rendered effective for use on currents higher than would be feasible otherwise.

125 As in the case of a cylinder, the position of the disk seems to be of importance, and its action is in a measure dependent on its distance from the anode. If, for any reason, it is desired to lessen the effect of the disk, the desired end may be attained by 130

moving it away from the anode into the narrow part of the tube. Also, I have found that when the hole in the disk is decreased in diameter, the de-ionizing action of the disk is increased. The effect of increasing the number of disks is to make higher voltages necessary to re-start the arc. This disk may be of platinum $\frac{3}{2}$ inch thick with a $\frac{1}{8}$ inch hole bored through the middle, and 5 may be set so as to fill the main tube. With 10 this construction, and a capacity of .25 mf., 4 amperes pulsating current can be obtained with a main line current less than 0.3 amperes. The pulsations are very regular, and 15 may be left running continuously without undergoing any change.

In the system shown in Fig. 10, the cooling fluid may, with advantage be very cold, and may be either air or may be oil circulated 20 vigorously.

The rectifying property of the mercury arc, since there is no back flow of current from the condenser, is a very powerful agent in promoting the quenching or de-ionization 25 of the arc. The discharge of the condensers through the arc, owing to the latter's property of conveying very large currents at low voltage is much more sudden than through a gap in the air, and this is a very desirable 30 quality.

Reference may again be made to the continuous oscillations which can be attained as above described with a vapor arc operating at a frequency of 100,000 per second, and 35 giving oscillations of a power of about 1000 watts at the high efficiency of transformation of 75%. As the losses in the mercury arc are small, the efficiency can be pushed even higher. This result is unusual and is 40 to be distinguished from any system giving intermittent condenser discharges at low frequency.

What I claim as new and desire to secure by Letters Patent of the United States is:— 45 1. The combination of a capacity circuit, a source of energy therefor, and a vapor electric device connected across said circuit and having inherent uni-directional conductivity at the maximum discharging potential 50 of said capacity circuit.

2. An apparatus for producing periodically varying currents of high frequency, comprising in combination a vapor electric device containing means for operating from 55 one of the main electrodes and auxiliary arc, a capacity circuit connected directly across said device, and a source of energy connected to supply current to said capacity circuit.

3. The combination of a capacity circuit, 60 a source of current, a device comprising an evacuated envelop, a cathode and an anode, said device having inherent unidirectional conductivity, ionizing means at the cathode for rendering said device conductive, and

means for deionizing in part the current-carrying path of said device between current pulsations, and connections between said electrodes and said capacity circuit.

4. In an apparatus for producing high frequency pulsations, a capacity circuit, a 70 mercury vapor device for producing current pulsations therein, said device being conductive for current in one direction and ar- 75 esting current flow in the opposite direc-

5. In a high frequency apparatus, the combination of a work circuit, a capacity circuit inductively related thereto, a metal vapor arc device comprising an evacuated envelop, connections between said capacity circuit and said device, means for continuously furnishing ionized vapor in said device and means for deionizing the arc path between successive current pulsations from 80 said capacity circuit.

6. In a high frequency apparatus, a work circuit, a capacity circuit inductively related thereto, a source of energy, and mercury vapor rectifying means operatively connected across said capacity circuit to produce current pulsations in said capacity circuit, said means being deionizable between successive current pulsations.

7. In a high frequency apparatus, a work circuit, a winding inductively related to said work circuit, a condenser connected to discharge through said winding, a vapor arc device having conductivity in one direction only connected to prevent reverse discharge from said condenser through said winding, 100 and means for deionizing at least in part the current carrying path of said device between successive condenser discharges.

8. In a high frequency apparatus, the combination of a capacity circuit, a device 105 having inherent unidirectional conductivity and comprising an evacuated envelop, and anode, an ionizable cathode and a deionizing conductor located between said electrode, and connections between said capacity circuit and said device.

9. The combination with a vapor electric device having a continuously operative ionizing means, of means for applying to the terminals of said device a periodically varying potential having a maximum value high enough to start an arc in said vapor device, and having a minimum value insufficient to support the arc.

10. The combination of a circuit containing electrical capacity and inductance, a source of energy therefor, a mercury vapor electric device connected across said circuit and having unidirectional conductivity at the maximum discharging potential of said 120 capacity, and an impedance device connected between said source and said vapor electric device.

11. The combination of a work circuit, a capacity circuit inductively related thereto, a source of energy for said capacity circuit, a mercury vapor electric device connected across said capacity circuit, having unidirectional conductivity at the maximum discharging potential of said capacity circuit, and being proportioned to dissipate heat from the arc path at such rate that the 10 arc will assume a condition of low conductivity between successive discharges of the capacity circuit, and means for artificially cooling said device to maintain the continuity and speed of current pulsations therein.
12. The combination of a capacity circuit, a source of energy for said circuit, and a vapor electric device connected across said capacity circuit and carrying energy discharged therefrom, said vapor electric device having an auxiliary arc. 15
13. The combination of a source of current, a rectifying electric device receiving energy from said source and having means for supplying conductive vapor, a capacity 20 circuit connected across said vapor electric device, and periodically discharging therethrough unidirectionally, and a work circuit inductively related to said capacity circuit.
14. In an apparatus for producing periodic currents of high frequency, the combination of a capacity circuit, a source of energy therefor, and means for conducting energy discharged from said capacity circuit, said conducting means having a continuously operative ionizing means, and being proportioned to dissipate heat at such rate that the vapor in said path will assume a condition of low conductivity between successive discharges of the capacity circuit. 25
15. The combination of a capacity circuit, a source of energy therefor, and means for discharging said capacity circuit, said means including a vapor path having continuously operative means for ionizing a 30 portion near the cathode only of said vapor path.
16. In a system for producing periodic currents of high frequency, the combination of a source of energy, a capacity circuit connected therewith, means providing a vapor path for the discharge of energy from said capacity circuit, said means being proportioned to dissipate heat from the arc path at such rate that the vapor path assume 35 a condition of low conductivity between successive discharges of the capacity circuit, and an auxiliary arc continuously operative to ionize a portion, at least, of said path.
17. In a system of electrical transformation, the combination of a capacity circuit, a mercury vapor rectifying device connected to regularly receive periodic unidirectional discharges from said capacity circuit, and means for circulating a non-conductive 40
- cooling fluid about said device to increase 45 the speed at which said discharges may occur.
18. In a system for producing high frequency current pulsations, the combination of a capacity circuit, an inclosed metal vapor electric device connected across said circuit and having unidirectional conductivity at the maximum discharge potential of said circuit, and means for externally cooling said vapor electric device to increase 70 75 the speed at which said capacity circuit may periodically discharge.
19. In an apparatus for producing periodic currents of high frequency, the combination of a capacity circuit, a source of energy therefor, and a vapor electric device connected across said source, said vapor electric device having a side branch and having a main arc path inclosed by an envelope proportioned to deionize the arc path 80 at such rate that the vapor device will assume a condition of low conductivity between successive discharges of the capacity circuit. 85
20. In a system for the transformation of electrical energy, the combination of a capacity circuit, a source of energy connected to charge said circuit and a vapor electric device providing a discharge path for energy from said capacity circuit, said vapor 90 electric device having a tubular portion through which the discharge may pass, proportioned to deionize the arc path at such rate that the vapor device will assume a condition of low conductivity between successive discharges of the capacity circuit, and means at one end thereof for maintaining 95 100 continuous ionization.
21. In a system for transforming electrical energy, the combination of a capacity circuit, a source of energy for charging said circuit, and a vapor electric device connected to receive energy discharged from said circuit, said vapor electric device having enlarged ends which are connected by a constricted tube proportioned to deionize the 105 arc path at such rate that the vapor device will assume a condition of low conductivity between successive discharges of the capacity circuit, said device having at its cathode 110 115 end only means for maintaining an auxiliary arc.
22. In an apparatus for producing high frequency currents, the combination of a work circuit, a capacity circuit inductively related thereto, a source of current connected to charge said capacity circuit, a vapor electric device connected across said capacity circuit, said device having a constricted tubular portion and large anode and cathode 120 125 chambers at the ends thereof, and means for circulating a cooling fluid about said vapor electric device.

23. The combination of a source of energy, a capacity circuit connected across said source, a vapor electric device connected to receive energy discharging from said capacity circuit, said vapor electric device having at the surface of its cathode a perforate body of metal.
24. In a system for the transformation of electrical energy, the combination of a work circuit, a winding inductively related thereto, a condenser in circuit with said winding, a source of energy for charging said condenser, and a vapor electric device proportioned to form a unilateral discharge path for said condenser, said vapor electric device having means for maintaining an auxiliary arc at the cathode.
25. In a system for producing periodic currents of high frequency, the combination of a capacity circuit, a source of energy therefor, means providing a vapor arc for the discharge of energy from said capacity circuit, and a conductive de-ionizing agent in operative relation to said arc.
26. In a system for the transformation of electrical energy, the combination of a capacity circuit, a source of energy for charging said circuit, and a vapor electric device containing a highly attenuated space and connected to receive energy discharged from said capacity circuit, said vapor electric device having a conductive de-ionizing body in its arc path.
27. The combination of a source of energy, a capacity circuit receiving current therefrom, and a vapor electric device connected across said capacity circuit, said vapor electric device having an inclosing envelop and a de-ionizing body located therein and having an opening through which the vapor arc may pass.
28. In a system for producing high frequency pulsations, the combination of a capacity circuit, a source of current therefor, an impedance device between said source and said circuit, a vapor electric device connected across said circuit, said device having a cooled anode, and a side branch, and having a de-ionizing conductor in the path of the arc, and means for circulating a cooling fluid about said vapor electric device.
29. In a system for producing electrical oscillations, the combination of a work circuit, a winding inductively related thereto, a condenser in circuit with said winding, a source of energy for charging said condenser, and a vapor electric device connected to receive the discharge of said condenser, said vapor electric device having a constricted tubular portion containing a de-ionizing conductor and having enlarged anode and cathode chambers and means for producing an auxiliary arc at the cathode.
30. In a system for the transformation of electrical energy, the combination of a work circuit, a winding inductively related thereto, a condenser in circuit with said winding, a vapor electric device connected across said condenser and said winding, said vapor electric device having an air-cooled anode and a large anode chamber and having a constricted tubular portion with a de-ionizing conductor therein, and having an enlarged cathode chamber and means for producing an auxiliary arc therein, a source of energy for supplying current to said vapor electric device, an impedance between said source and said device, and means for circulating a cooling fluid about said vapor electric device.
31. An apparatus for producing periodic currents of high frequency comprising a capacity circuit, a source of energy for charging said circuit, a cathode directly connected to one side of said circuit, an anode directly connected to the other side, and a second anode coöperating with said cathode to maintain a discharge path over which said capacity circuit may discharge.
32. The combination of a source of energy, a capacity circuit connected across said source, a cathode directly connected to one side of said capacity circuit, an anode directly connected to the other side, a second anode and means for continuously maintaining an arc between said second anode and said cathode.
33. A discharge device for a capacity circuit comprising an evacuated envelop having a constricted tubular portion, electrodes in said envelop, and a de-ionizing conductor in said constricted portion.
34. A discharge device for a capacity circuit comprising an evacuated envelop, an anode and a cathode therein, chambers about said anode and cathode respectively, a constricted tubular portion connecting said chambers, and a conductor in said tubular portion.
35. A discharge device for capacity circuits comprising an evacuated envelop having a large anode chamber, a cathode chamber and a constricted tubular portion connecting said chambers, a hollow air-cooled main anode for said envelop, means for continuously ionizing the lower end of said envelop to facilitate the starting of an arc from said main anode, and a de-ionizing conductor in the path of said arc.
36. A discharge device for a capacity circuit comprising an envelop inclosing an evacuated space, electrodes therein between which current pulsations may pass, and conductive de-ionizing means within said device in the path of the arc to increase the rapidity at which successive current pulsations may follow one another.
37. A discharge device for a circuit having electrical capacity, said device comprising

- ing an evacuated envelop, electrodes within said envelop between which an arc may be established, and means within said envelop for effecting rapid de-ionization of the path 6: of said arc, whereby the voltage at which successive discharge may start is maintained substantially invariable.
38. The combination with a condenser, of a device having a discharge path for said 10 condenser, said device having ionizing means for one part of said path and de-ionizing means in another part thereof.
39. A discharge device for a condenser, said device having an envelop affording a 15 constricted path for current, and having means for maintaining a continuously operating arc at one end of said path, said device also having de-ionizing means in another part thereof.
- 20 40. The method of producing intermittent currents in a capacity circuit which consists in charging and periodically discharging said circuit through a vapor electric device having inherent unilateral conductivity at 25 the maximum potential of said discharge.
41. The method of producing periodic currents in a capacity circuit which consists in periodically discharging said circuit through a vapor electric device, maintaining continuous ionization in a portion of 30 said device, and controlling the character of said currents by limiting the movements of the cathode spot of said vapor device.
42. The method of producing periodic 35 currents in a capacity circuit which consists in periodically discharging said circuit through a vapor electric device which has ionizing means continuously operative, and controlling the character of said periodic 40 current by controlling the temperature of said electric device.
43. The method of controlling the character of periodic currents produced in a capacity circuit connected to a source of energy and shunted by a vapor arc, which 45 consists in confining said arc to a constricted path and cooling said arc by circulating a cooling fluid about said constricted path.
44. The method of controlling the character 50 of periodic currents produced in a capacity circuit connected to a source of energy and shunted by a vapor electric device having an anode and a cathode, which method consists in discharging said capacity 55 circuit at a single impulse between said anode and said cathode, maintaining continuous ionization in the neighborhood of said cathode, and effecting rapid de-ionization in the neighborhood of said anode.
- 60 45. The method of controlling the action of a capacity circuit shunted by a vapor electric device having an anode, a cathode and an envelop with a constricted tubular portion, which method consists in maintain-
- ing ionization near said cathode, and effecting rapid de-ionization at other parts of said envelop by projecting a cooling fluid against the walls thereof.
46. The method of increasing the speed at which a capacity circuit can discharge 70 through a vapor electric device which has an evacuated envelop, an anode and a cathode, said method consisting in maintaining ionization near the cathode of said device, and confining the flow of current from said 75 anode to said cathode within a narrow path.
47. The method of producing periodic currents in a capacity circuit connected to a source of energy and shunted by a vapor electric device which has an anode and a cathode, said method consisting in maintaining continuous ionization in the neighborhood of said cathode, and effecting rapid de-ionization in the neighborhood of said anode by cooling said anode with a circulating 80 fluid, whereby the capacity circuit discharges by separate impulses in one direction only.
48. The method of producing periodic currents in a condenser connected to a source 90 of energy and shunted by an evacuated vapor electric device, which consists in periodically charging the condenser from the source and discharging the condenser at a single impulse through the vapor electric device, and effecting speedy de-ionization by externally cooling a portion of said device.
49. The method of producing periodic currents in a capacity circuit connected to a source of energy and shunted by a vapor 100 electric device which has an anode and a cathode, said method consisting in periodically charging said capacity circuit from said source, discharging said circuit through said vapor electric device, maintaining continuous ionization near the cathode of said device, circulating a cooling fluid in contact with said anode, and effecting speedy de-ionization of a portion of the arc path by circulating a cool fluid about a constricted 110 portion of the vapor device wherein the arc passes in contact with a conductive body.
50. The method of transforming energy in a system having a capacity circuit shunted by a vapor electric device, which consists in maintaining continuous ionization at the cathode in said device, discharging said capacity circuit therethrough, and applying the pulsations thus produced to initiate oscillations in a work circuit co-operatively related to said capacity circuit.
51. The method of distributing electrical energy, which consists in supplying current to a capacity circuit, periodically diverting energy from said circuit through an electric discharge device having inherent unidirectional conductivity, and having a continuously operative ionizing means, deion-

izing the current carrying path between successive pulsations of current, and inductively transforming the pulsations thus produced into oscillating current of the desired voltage.

52. The method of producing periodic currents in a capacity circuit shunted by a device affording an electric discharge path of inherent unidirectional conductivity having ionizing means constantly operative, which consists in periodically diverting en-

ergy from said circuit through said path, and controlling the character of the pulsating current thus produced by de-ionizing said path.

15
In witness whereof, I have hereunto set my hand this 13th day of June, 1910.

EZECHIEL WEINTRAUB.

Witnesses:
